UNITED STATES PATENT OFFICE.

LEONARD C. TIEFEL, OF ROCHESTER, NEW YORK, ASSIGNOR OF ONE-HALF
TO GERMAIN MATTISON, OF SAME PLACE.

COMBINED EXTENSION AND STEP LADDER.

SPECIFICATION forming part of Letters Patent No. 608,929, dated August 9, 1898.

Application filed April 25, 1898. Serial No. 678,797. (No model.)

To all whom it may concern:

Be it known that I, LEONARD C. TIEFEL, a citizen of the United States, residing at Rochester, in the county of Monroe and State of New York, have invented a new and useful Improvement in a Combined Extension and Step Ladder, which improvement is fully set forth in the following specification and shown in the accompanying drawings.

My invention is a combined step and extension ladder consisting of two parts or sections joined or connected to act together. These sections are so formed and connected that in addition to serving jointly as a step-ladder or an extension-ladder they may be also so arranged or disposed upon each other that the device in the form of a step-ladder may rest upon the steps of a flight of stairs, or one section may rest upon the floor and the other section upon a table, counter, window, stool, or other elevated object, as convenience or need may require.

The invention is hereinafter fully described, and more particularly pointed out in the claims.

Referring to the drawings, Figure 1 is a front elevation of the device closed. Fig. 2 is a side elevation seen as indicated by arrow 2 in Fig. 1, the device being spread as a step-ladder. Fig. 3 is a side elevation of the upper end of the device, better showing the relation of the parts when closed. Fig. 4 is an elevation of the upper parts of the device when spread, sectioned on the dotted line 4 4 in Fig. 1. Fig. 5 shows the device formed as an extension-ladder. Figs. 6 and 7 show the device as a step-ladder adapted to rest on objects at different elevations. Fig. 8 is a top view indicated by arrow in Fig. 4, parts being broken away. Figs. 3, 4, and 8 are drawn to a scale larger, and Figs. 6 and 7 to a scale smaller, than that of Figs. 1, 2, and 5.

Referring to the drawings, A is the front section, and B the rear section, of the ladder, joined or connected at the top of the front section by a horizontal angular yoke or confining-bar *a*, of iron. This yoke or bar crosses the front section at its rear side, having its ends turned or bent down against the outside surfaces, respectively, of the section and secured to the latter by pivot-bolts *b b*, so as to

swing freely thereon. The section B is held by and confined within the yoke, being adapted, however, to slide longitudinally to any distance upward through said yoke.

55

As constructed the side rails *c c* of the section A are spread or flared at the bottom, the rails *d d* of the rear section B being straight and parallel and fall just within said rails *c c* at their upper ends, as shown in Fig. 1.

60

The rungs *e* of the section B are made to reach through the rails *d d* and project some distance at the sides thereof, as shown in Figs. 1, 3, and 8, these projecting ends *e'* being cylindrical. The section A is provided with two seats or rests *f f* on its rear side, adapted to receive and hold the projecting ends *e'* of either rung *e*, as shown in Figs. 1 and 3, when the sections are brought together side by side. Now by sliding the section B endwise up 70 through the yoke *a* any one of the rungs *e* below the upper one may be caused to occupy said seats or rests, thus making an extension-ladder of the device, as shown in Fig. 5. If the ladder, as shown in said Fig. 5, be weighted, as by a person occupying it, the tendency would be to bend or force the middle of the ladder in the direction indicated by arrow *g* and swing the lower end of the section B away from the section A; but as the rests *f f* 80 are formed to securely hold the projecting parts *e'* when pressed therein by the weight of the section B, and thus prevent the separation of the sections, the ladder as a whole is firm when in its extended form, the front 85 side of the section B, it being understood, bearing against the rear edge of the upper step *h* of the section A.

75

The section B is provided on its front side, at its upper end, with projecting stops *i i*, 90 Figs. 4 and 8, rigid with the section and adapted to cross and bear upon the upper step *h* of the section A when the device is put in the form of a step-ladder. These stops encountering said upper step and coacting 95 with the confining-bar or yoke *a* serve to limit the distance to which the lower ends of the sections may be spread when opening them to the form of a step-ladder. The yoke, while not directly secured to the rear section, turns with the latter when the sections are 100 opened or closed at the bottom, always main-

section rest upon an elevated object, as a step of a flight of stairs C or a counter D, Figs. 6 and 7, said rear section is both elevated and 20 swung away from the front section. In this form and position of the ladder the projections e' bear against the rails c c of the front section within the yoke, as indicated, the latter preventing said projections from passing 25 by or escaping from the ends of said rails. The structure is thus made firm in its position, in which the sections are differently elevated.

What I claim as my invention is—

when the two sections are spread, said projections together with the yoke, serving to hold the rear section in position, substantially as shown and described.

50

In witness whereof I have hereunto set my hand, this 21st day of April, 1898, in the presence of two subscribing witnesses.

LEONARD C. TIEFEL.
